VALUE SETTING REGISTER ACTUATING DEVICE

Elbert Fowler, Mount Vernon, N. Y., assignor to Pitney-Bowes, Inc., Stamford, Conn., a corporation of Delaware

Application July 23, 1947, Serial No. 762,858

3 Claims. (Cl. 235—31)

1

This invention relates to a register actuating device and is particularly adapted for use in effecting the accumulation of a selected value in registering mechanism of a postage printing and metering device.

In a postage printing and metering device, the value of postage which it is desired to print is first set up in printing wheels of a printing device and in actuator mechanism of a metering device, then, during a printing cycle of operation, the actuator mechanism effects operation of the registering device to accumulate the printed value therein. It is with regard to the latter operation that the device of this invention is particularly concerned.

It is the object of the invention to provide an improved register actuating device wherein the setting of a value will effect the adjustment of an element, which, during a cycle of operation, will guide the motion of differentially driven means and an accumulator wheel drive connected therewith, and thereby control the accumulation of the value in accordance with the setting.

With the above and other objects in view, which will appear as the description proceeds, the invention resides in the combination and arrangement of parts and in the details of construction hereinafter described and claimed, it being understood that various changes in the precise embodiment of the invention herein disclosed may be made within the scope of what is claimed without departing from the spirit of the invention.

A preferred embodiment of the invention is illustrated in the accompanying drawings, wherein;

Fig. 1 is a sectional view through the meter unit casing and includes registering mechanism, value setting, register actuating and driving mechanism, with the setting mechanism set to the "9" value position;

Fig. 2 is an operational view showing the actuator mechanism in the position assumed after the "9" value has been accumulated in the registering mechanism;

Fig. 3 is a view of the setting and registering actuating mechanism, with the setting mechanism set in a "0" position;

Fig. 4 is an operational view similar to Fig. 3 with the register actuating mechanism shown at its extreme forward stroke position, and showing how the accumulator driving unit remained fixed during the actuating mechanism movement;

Fig. 5 is a plan view of the elements shown in Fig. 1, with the meter casing removed;

2

Fig. 6 is a detailed view of an accumulator wheel clutch controlled drive taken in the direction of the arrow 6 on Fig. 5; and

Fig. 7 is a perspective view of a differential unit associated with the actuator mechanism.

Referring to the drawings in detail, a meter unit casing 10 encloses registering mechanism generally indicated at A, selection mechanism B, actuating mechanism C, and drive mechanism D.

10 The registering mechanism A includes accumulator wheels 14—14, each of which have an associated toothed wheel 15 secured thereto and are suitably mounted on shafts 16—16 supported within the meter casing 10. A plurality of accumulator wheels of the internal differential drive type are provided in each group, and suitable Geneva tens transfer elements are provided, as indicated at 17—17. By means of a common drive gear 18, which meshes with the toothed 20 wheels 15—15, the accumulator wheels 14—14 are adapted to be driven during a cycle of operation. Referring to Fig. 6, a pinion 19 is shown united with the gear 18 by means of a clutch 21. Both the gear 18 and pinion 19 are supported on a 25 shaft 22, which shaft is suitably supported within the meter casing 10.

The selection mechanism B comprises a settable lever 23, which lever is pivotally mounted within a bracket 24. A circular portion 25, projecting from one side of the lever 23, fits within a circular opening 26 in the bracket 24 and provides a pivotal mounting for said settable lever. At the lower end of the settable lever 23, a cam member 27 is provided, which member includes 30 an arcuate cam slot 28 therein. A spring urged detent 29 is also provided on said settable lever 23, which cooperates with a notched detent rack 31 to effectively space the setting of said settable lever opposite each of the several values indicated in Fig. 1.

40 Differential actuator mechanism C is provided, which is adapted to actuate the registering mechanism during a cycle of operation. Said actuator mechanism comprises a toothed member 45 or gear segment 32, which is freely mounted upon a shaft 33 and is adapted to mesh with the clutch pinion 19. The shaft 33 is suitably supported within the casing 10. Two oppositely disposed levers 35 and 36 are freely mounted on a stud 34, the lever 35 being upwardly disposed and the lever 36 being downwardly disposed. The free end of the upwardly disposed lever 35 is joined with the free end of a similar lever 37 which is fixed to the shaft 33. Also, the free end of the 50 downwardly disposed lever 36 is joined with the

free end of an arm 38 projecting downwardly from the gear segment 32. Said levers 35, 36, 37 and the arm 38, when joined together in the manner described and shown, form a parallel linkage structure. A cam roller 41 is also carried by the stud 34 and is guided within the cam slot 28 of the cam member 27.

When the settable lever is in the value "9" position shown in Fig. 1, the arcuate cam slot 28 is concentric with the center of the segment gear shaft 33, but during adjustment of the settable lever, the cam slot 28 takes a different position relative to the shaft 33 for each value setting. The stroke of the gear segment 32 therefore, is dependent upon the position of the cam member 27.

In the value "9" position (Fig. 1) of the setting lever 23 and its associated cam member 27, the cam roller 41, during a cycle of operation, will be moved through the path of the arcuate cam slot 28 to the lowermost end thereof, as indicated in Fig. 2. Said motion of the cam roller will effect motion of the parallel linkage structure and the rotation of the gear segment 32 about the shaft 33, to thereby rotate associated accumulator wheels nine spaces. It will be noted that the parallel linkage structure does not alter its shape during actuation of the value "9," due to the concentric relation of the cam slot with the shaft 33.

When the setting lever is in the "0" position, as indicated in Figs. 3 and 4, the cam roller 41, upon moving to the lower end of the arcuate cam slot 28, will cause the parallel linkage structure to continually change its shape during the movement of the cam roller without effecting any change in position of the gear segment 32. The accumulator wheels associated with the "0" setting remain unmoved. Each of the intermediate value settings, 1 through 8, will effect a variable control of the parallel linkage structure to produce rotation of the segment gear 32 and that of the pinion 19, in accordance with the value set.

A drive is provided to effect oscillation of the parallel linkage structure, which drive includes a lever 42 fixed to the shaft 33. A link 43 has one end joined with the free end of the lever 42 and has a cam roller 44 mounted at its opposite end. Said cam roller 44 is adapted to engage a cam slot 45 provided within a rotatable drum cam unit 46, carried by a main drive shaft 47. The rotation of the shaft 47 is adapted to effect a printing cycle of operation. The drum cam unit 46 is adapted to be driven by means of a drive gear 48, which gear may be driven by any suitable manual or motor driven means. During each rotation of the drum cam unit 46 therefore, the lever 42, shaft 33 and lever 37 will be oscillated to thus effect the drive of the parallel linkage structure and move the cam roller 41 through the cam slot 28, which slot will control the effective movement of the gear segment 32.

A further cam portion is provided on the drum cam unit 46, and comprises a cam slot 49, which is adapted to control the motion of a horizontally disposed rocker lever 51, best shown in Fig. 5. Said rocker lever is pivotally mounted on a support 52, and has a cam roller 53 at one end, and a projection 54 at the other end thereof. A clutch shifting yoke 55 is adapted to straddle the sides of the clutch pinion 19, and has a notch 56 therein which is engaged by the projection 54. Said cam slot 49 is arranged so that the rocker lever 51 will be rocked after the set

value has been registered in the accumulator wheels of the registering mechanism, to thus release the drive pinion 19 from its clutch drive position when the cam roller 41 and parallel linkage structure return from their actuating to their initial positions. Upon arriving at the initial position, the cam slot 49 effects rocking of the lever 51 in an opposite direction to provide reengagement of the clutch 21.

Having described the invention, what is claimed is:

1. In a register actuating device, an accumulator wheel, a toothed segment member geared to said accumulator wheel, a value setting member having a cam portion associated therewith, differential means comprising a parallel linkage structure having one point connected with and controlled by the cam portion and having the actuating point thereof arranged to control the position of the toothed segment, an oscillating drive for said differential means, whereby the segment member is rocked in accordance with the differential movement of the parallel linkage structure as controlled by the position of the cam in each value position, and means to disconnect the geared connection between the accumulator wheel and segment member after the selected value has been accumulated in the accumulator wheel.
2. In a register actuating device, an accumulator wheel, a toothed segment member geared to said accumulator wheel, a value setting member having a cam portion associated therewith, a follower roller engaging said cam, differential means comprising a parallel linkage structure having one point associated with the follower roller and the actuating point thereof associated with the toothed segment member, an oscillating drive for said differential means, whereby the toothed segment member is rocked in accordance with a differential movement of the parallel linkage structure as controlled by the position of the cam in each value position, and means to disconnect the geared connection between the accumulator wheel and segment member after the selected value has been accumulated in the accumulator wheel.
3. In a register actuating device, an accumulator wheel, a toothed member geared to said accumulator wheel, a value setting member, differential means comprising a parallel linkage structure having a pivotal point and arranged to rock the toothed member when moved about said pivotal point, a cam associated with the value setting member and having an arcuate cam slot concentric with the parallel linkage pivot point when the setting member is adjusted to the position of highest value, a point of said parallel linkage opposite the pivot point being engaged with the cam slot and controlled thereby, means to oscillate the parallel linkage structure about its pivotal point, whereby, when the setting member is set in the position of highest value the shape of the parallel linkage structure will remain unchanged during oscillation thereof, and for each succeeding lower value setting the parallel linkage structure will differentially alter its shape to effect a stroke of the toothed member in accordance with the value set, and means to disconnect the geared connection between the accumulator wheel and segment member after the selected value has been accumulated in the accumulator wheel.

ELBERT FOWLER.
